UNITED STATES PATENT OFFICE

PAUL REUTER-LORENZEN, OF DETROIT, MICHIGAN, ASSIGNOR TO MORGAN & WRIGHT,
A CORPORATION OF MICHIGAN

DESIGN FOR A TIRE

Application filed March 29, 1930. Serial No. 35,067. Term of patent 14 years.

To all whom it may concern:

Be it known that I, PAUL REUTER-LORENZEN, a citizen of Denmark, residing at Detroit, county of Wayne, State of Michigan, have invented a new, original, and ornamental Design for Tires, of which the following is a specification, reference being had to the accompanying drawings, forming part thereof, wherein:

Figure 1 is a perspective view of a tire showing my new design and

Fig. 2 is a cross sectional view of the tire.

The tire is characterized by having a mottled colored side wall extending upwardly from the beads to the edges of the circumferential shoulder ribs and tire tread.

I claim:

The ornamental design for a tire as shown and described.

Signed at Detroit, in the county of Wayne, and State of Michigan, this 20th day of March, 1930.

PAUL REUTER-LORENZEN.
